MODULAR HOME

Roger A. King and Keith O. Burton, Elkhart, Ind., assignors to Bur Kin Homes Corporation, White Pigeon, Mich.

Filed Jan. 11, 1971, Ser. No. 105,761

Term of patent 14 years

Int. Cl. D25—03

U.S. Cl. D13—1

Fig. 1

Fig. 2

FIG. 1 is a front elevational view of a modular home embodying the present design;

FIG. 2 is a rear elevational view of the modular home shown in FIG. 1; and

FIG. 3 is an elevational view of one side of the modular home shown in the preceding figures.

The side of the modular home opposite the one shown in the drawings is otherwise identical in construction and appearance to the one in the drawings.

We claim:

The ornamental design for a modular home, as shown and described.
